UNITED STATES PATENT OFFICE

95,404

DESIGN FOR A TEXTILE FABRIC

Curt Erwin Forstmann, Montclair, N. J.

Application January 2, 1935, Serial No. 54,688

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing forming part thereof.

In the drawing, the sole figure of which is a plan view of a piece of the textile fabric embodying the design of the present invention, the cloth depicted is of a single color. The dominant feature of the design is a repeated motif indicated between the broken lines in the drawing constituted as follows: a group of two parallel adjacent rows of spaced apart elongated elevations, the

rows being staggered so that the elevations of one row bridge the intervening spaces of the adjacent row. Contiguous to this group is a continuous rectilinear elevation, and next to this a second group of two rows similar to the first group, but having the staggered elevations about one and one-half times the length of the elevations in the first group of rows. Contiguous to this second group of rows is a continuous rectilinear elevation. The continuous elevations are delineated into sections by narrow transverse linear prominences.

I claim:

The ornamental design for a textile fabric as shown and described.

CURT ERWIN FORSTMANN.
